(57) **CLAIM**

The ornamental design for a motorcycle trunk light as shown and described.

DESCRIPTION

FIG. 1 is a perspective view of the motorcycle trunk light. FIG. 2 is a front elevational view thereof.

FIG. 3 is a rear elevational view thereof.

FIG. 4 is a first side view thereof.

FIG. 5 is a second side view thereof, opposite the first side view.

FIG. 6 is a top side view thereof; and,

FIG. 7 is a bottom side view thereof.

The rear surface of the motorcycle trunk light shown in broken lines form no part of the claimed design.

FIGS. 1-7 show a first embodiment. A claimed second embodiment is a mirror image of the first embodiment but is not shown in the drawings.
